UNITED STATES PATENT OFFICE.

WILLIAM SOUTHWICK, OF GORDON, ONTARIO, CANADA.

WHIFFLETREE.

SPECIFICATION forming part of Letters Patent No. 364,314, dated June 7, 1887.

Application filed January 13, 1887. Serial No. 224,190. (No model.)

To all whom it may concern:

Be it known that I, WILLIAM SOUTHWICK, of Gordon, in the county of Essex and Province of Ontario, Canada, have invented new and useful Improvements in Whiffletrees; and I do hereby declare that the following is a full, clear, and exact description thereof, reference being had to the accompanying drawings, which form a part of this specification.

10 This invention relates to certain new and useful improvements in the construction of whiffletrees of that class which are designed to spring or yield, and thus render the starting of a load more easy upon a horse.

15 The invention consists in the peculiar construction of the whiffletree, as hereinafter set forth.

In the accompanying drawings, which form a part of this specification, my invention is shown in elevation and as attached to the shafts of a cart, and in which A represents the whiffletree proper, which is pivotally secured in any convenient manner to the draw or cross bar of the shaft. This whiffletree is constructed, 25 preferably, of steel, and at its longitudinal center is provided with an enlargement or boss, a, for receiving the pivot-pin, the two ends of the whiffletree being decreased in thickness and terminating in the arms b, which are provided with suitable hooks or other devices by 30 means of which the traces can be attached thereto.

The side d of the whiffletree adjacent to the cross-bar of the thills is straight and parallel 35 with the said cross-bar for its entire length, as shown, the enlargement or boss a being upon the opposite or front side of said whiffletree, the sides of the arms b running parallel with

each other for about two-thirds of their length to the point e, where the enlargement 40 commences. This construction gives greater elasticity to the arms b and avoids all tendency of the whiffletree to break at or near its center, and in this peculiar construction lies the gist 45 of my invention.

By this construction a whiffletree is provided which has sufficient elasticity in it to materially lessen the liability of injury to the horse's shoulders in starting a load and in drawing the same, as the resiliency of the 50 spring will keep the traces taut under all ordinary circumstances and prevent the jerky motion that is derived from the use of a stiff whiffletree.

I am aware of the Patent No. 225,250, and 55 make no claim to the construction shown therein as forming part of my invention, but limit myself to my peculiar construction, attaching importance to the form of the whiffletree shown and above described.

60 What I claim as my invention is—
The whiffletree described, formed of a single piece of steel having a straight side, d, enlargement a, substantially in its center, upon the side opposite the said straight side, and the 65 spring-arms b, the sides of which are parallel from the points e to their ends, substantially as shown and described, and for the purpose specified.

In testimony that I claim the above as my 70 invention I have hereunto set my hand.

WM. SOUTHWICK.
